UNITED STATES PATENT OFFICE.

KARL MAX ERICH ZWINKEL, OF DENVILLE, NEW JERSEY.

TUNNEL AIRBOAT.

Application filed August 11, 1928. Serial No. 299,045.

The invention relates to an airplane preferably adapted for emergency use as a boat upon the water as well as for flying in the air. One of the objects of the invention is to increase the efficiency of the motors employed for driving the propellers and thereby increase the possible speed of the airplane.

A further object of the invention is to render the motors and propellers accessible from the interior of the machine at all times and in all conditions of weather.

These results are accomplished by providing one or more tubes extending longitudinally of the machine with which tubes a plurality of motor driven propellers communicate. In the preferred form a single centrally arranged tube is employed and two rows of propellers communicate with the tube. These propellers are so arranged that the compression within the tube increases gradually from front to rear. To accomplish this the speed of rotation of the propellers progressively increases from front to rear, and also the pitch of the propellers increases progressively from front to rear.

The invention may be more readily understood by reference to the accompanying drawings in which

Fig. 1 is a side elevation showing an airplane equipped with a preferred form of my invention.

Fig. 2 is a top plan view of the same.

Fig. 3 is a vertical sectional view through the machine showing the arrangement of motors and the central longitudinal tube.

Fig. 4 is a fragmentary side elevation on an enlarged scale showing one of the propellers and the motor for operating the same, and also showing a slot leading from the exterior of the machine to the central tube.

Fig. 5 is a detailed sectional view showing a modification in which a full tube is employed and in which the propellers are mounted wholly within the tube.

Referring to the drawings in detail, the reference numeral 10 designates the hollow body of an airplane which is preferably boat-shaped, and water-tight so as to permit of emergency use as a boat. This boat is preferably of metallic construction, a light metal, such as aluminum, being employed. The device is equipped with common wings indicated at 11, the present device being shown as of the monoplane type, although any number of wings may be employed.

Within the body of the boat are freight,

fuel and passenger compartments which are entirely protected from the weather. These are indicated at 12, 12a, 13 and 14.

The important feature of the invention resides in the provision of a longitudinal tube 15 which extends the entire length of the machine from front to rear. The arrangement shown in Figs. 1 to 4 is of the half tube type and is centrally arranged. If desired, more than one tube may be employed, as for example where two tubes are used, one on each side of the body of the machine.

Means are provided for progressively increasing the compression from front to rear within the longitudinal tube. As shown in Figs. 1 to 4, two rows of single motors and propellers operated thereby are employed. One of these propellers is shown in detail in Fig. 4, and is designated by the numeral 16. 75 A slot 17 in the body of the machine provides a means of communication between the outer atmosphere and the longitudinal tube and the propeller operates within this slot. Each propeller is actuated by a suitable motor 18, 80 herein shown as located at the rear of its respective propeller.

As shown in Fig. 2, the propellers in the two rows are staggered. In order to provide for gradually increasing the compression 85 from the foremost propeller to the one at the rear, the speed of rotation of the propellers is preferably gradually increasing from front to rear and in addition the pitch should be progressively increasing from front to rear. 90 The desired result might be accomplished by having all motors rotate at the same speed, but with progressively increasing pitch or by having the pitch of all of the propellers the same, but with progressively increasing 95 speed. The preferred arrangement, however, is with both speed and pitch progressively increasing from front to rear.

Referring to Fig. 3, it will be noted that due to the form of the central tube which 100 has inset portions at 19, the propellers may be mounted so as to obtain maximum efficiency.

It will also be noted that spaces are provided at 20 which are in direct communication with the passenger compartment 13, 105 through which spaces access may be had to the propellers and motors without exposure to the weather.

While in my preferred form I have shown the propellers rotating partially within the central tube and partially in the outside atmosphere, it is possible to have the propellers

located entirely within a central tube, as shown in Fig. 5, in which I have employed what I term as a full tube 21, as distinguished from the half tube 15 shown in Fig. 3, employed in the preferred embodiment of the invention. The advantage of the half tube arrangement resides in the fact that by having the propeller rotate in the outside atmosphere as well as in the tube, back draft 10 is prevented and thus greater efficiency is secured. I do not wish, however, to confine my invention to this arrangement, or to the use of a single tube.

The airplane may be equipped with the usual horizontal and vertical air rudders 22 and 23 and in addition an extension 24 from the vertical rudder 23 may be provided making the device more efficient for use on the water.

What I claim as new and desire to secure by Letters Patent is:—

1. An airplane comprising a hollow metal body, a central tube extending longitudinally from front to rear of said body, a plurality

of propellers mounted in two rows, one row 25 on each side of the central tube and in staggered relation to each other, said propellers rotating partially within the central tube and partially in communication with the outer atmosphere.

2. In an airplane, a longitudinal tube, means for producing compression within the tube comprising two rows of propellers arranged in staggered relation to each other.

3. An airplane comprising a body, a tube 35 extending longitudinally from front to rear of said body, and a plurality of propellers mounted in two rows, one row on each side of the tube, and in staggered relation to each other.

4. An airplane comprising a body, a central tube extending longitudinally from front to rear of said body, a plurality of propellers mounted in two rows, one row on each side of the central tube, and in staggered relation 45 to each other.

In testimony whereof I affix my signature.
KARL MAX ERICH ZWINKEL.
